UPHOLSTERY PAD STUFFING MACHINERY

Thomas L. McJoynt, Janesville, Wis.

Application May 11, 1933, Serial No. 670,436

5 Claims. (Cl. 226—43)

My invention relates generally to improved means for stuffing upholstery pads or the like, the mechanism employed being somewhat the same as that disclosed in my co-pending application, Serial Number 665,735 filed April 12, 1933 covering Method of stuffing pads.

The principal difference between the structure shown and described herein and that in my co-pending application is the mechanism employed for distending the unfilled pad as to readily receive the filling nozzle, the main object of the invention being the employment of means to accelerate the mechanical pad stuffing methods heretofore employed; another object is to eliminate certain parts of the mechanism heretofore deemed essential in automatic pad stuffing equipment.

To more fully understand my invention, reference should be had to the accompanying drawings in which:

Fig. 1 is a side plan view of the mechanism employed, the parts shown being partially in section and partially fragmentary;

Fig. 2 is a longitudinal fragmentary sectional view of a pad mold;

Fig. 3 is another fragmentary sectional view of a pad mold;

Fig. 4 is a fragmentary plan view of one of the rubber pad locking devices which forms a part of my invention;

Fig. 5 is a sectional view along the line 5—5 of Fig. 4;

Fig. 6 is a fragmentary plan view of the front of the mold;

Fig. 7 is a fragmentary view partially in plan and partially in section disclosing the mechanism for locking the mold and clamping a pad therein;

Fig. 8 is a fragmentary plan view of a plate having extended collars over which the different sections of an unfilled pad are adapted to be fitted;

Fig. 9 is a cross sectional view along the line 9—9 of Fig. 8;

Fig. 10 is a fragmentary front plan view of the carriage frame on which pads are fed to the stuffing operators;

Fig. 11 is another fragmentary view partially in section and partially in plan of a pad mold; and

Fig. 12 is a top fragmentary plan view of a mold showing a portion of the cover broken away to reveal the pad in the process of being filled.

55 In the drawings the numeral 10 is used to

designate a hopper from which stuffing is drawn into a blast fan 11 and from thence blown into chutes 12 and 13 alternately.

A valve 14 having its axis at 15 controls the flow of material from one chute to the other by manual adjustment by the stuffing operators so that the operation of pad stuffing is carried on continuously, there being no necessity of shutting off the blast fan while one operator changes the loading nozzle from one section of a pad to another due to the fact that while one operator is filling one section of his pad, the operator of the other nozzle is adjusting his nozzle preparatory to filling a section in the pad before him. Therefore, a continuous flow of the material is preserved and such flow alternates between the nozzles. This portion of my invention is covered in Patent Number 1,828,673 granted October 20, 1931 and my other co-pending application filed since that time and for that reason it is not thought necessary or essential to discuss the said process in detail except as it pertains to the invention covered by the claims herein.

The numerals 16 and 17 are used to designate nozzles, the larger tubular ends of which are fixed to the open ends of chutes 12 and 13. The said nozzles 16 and 17 are reduced throughout a portion of their length, said reduction extending from approximately one-half the distance between the ends to the outer discharge ends thereof.

As illustrated in Figure 1, outlet elements in the form of tubes 18 are slidably fitted over the nozzles 16 and 17 and are somewhat greater in length than the mold so that the same may be extended to the extreme inner portions of the pads within the mold for the discharge of filling material at such portions of the pads without, of course, becoming disconnected from the associated nozzles.

An emergency exhaust 20 is positioned between the fan 11 and the valve 14 so that when, for some reason or other, it is necessary to shut off both filling nozzles, an auxiliary means is afforded of diverting the stuffing as it comes from the blower. This auxiliary exhaust is usually connected back to the hopper so that in the interim of total shut-off of the nozzle (which is accomplished by closing a valve 21 located directly ahead of the emergency exhaust orifice) 50 stuffing is passed back into the hopper, thus preventing congestion of the stuffing immediately back of the valve 21. The auxiliary exhaust valve, in addition to the stuffing diversion valve 55

14, is controlled by either of the two nozzle operators by means of ropes or levers.

A track frame, on which are mounted parallel spaced tracks 22 and 23, is positioned adjacent 5 the orifices of the nozzles, the said tracks being so spaced as to permit the alignment of pad molds with the discharge orifices of the staggered parallel nozzles, one of the said nozzles being positioned to fill pads in molds riding on one 10 track and the other to fill pads on the adjacent track.

To facilitate the travel of the molds along the track, the said molds are provided with flanged wheels 24, the said wheels being suspended from 15 the under sides of the molds.

The mold per se, the construction of which is the essence of the invention herein described, has a solid bottom 25 and a perforated hinged top 26; the said perforated top is usually made of 20 mesh wire which is affixed to a frame 27. The top and bottom members of the said mold are relatively adjustable through the medium of adjustable hinge members 29. The rear end of the 25 said mold is also perforated and formed of a frame 30 to which a screen 31 is affixed.

Locking members 32 are provided, the said locking members being affixed to the hinged top of the said mold and the bottom end of the locking member is so formed as to cause the 30 top to be locked to the base when the said hinged top is in closed position. These locking members are also adjustable so that the lock is operative at any adjustment of the height of the mold. The end opposite the hinged end of the mold, which 35 we will hereafter designate as the front end, is open and the top and bottom members of the mold are spaced from each other through the medium of adjustable stop members 33.

A rubber friction member 34 extends across 40 the front end of the hinged top on the under-side thereof, and on the bottom of the said mold adjacent to and aligned with the top friction member is another rubber friction member 35. Both of the said members or yieldable pressure 45 transmitting mediums consist of U-shaped metal frames in which a soft rubber strip is vulcanized. The lower friction member is adjustable relative to the top friction member through the medium of adjustable nuts and bolts 36. The function of the heretofore described friction members will be 50 explained hereinafter.

A rectangular plate 37 closes the front of the mold when an empty pad to be filled is positioned therein. Said plate 37 has orifices 38, the edges of which are inturned to form collars 39; the said 55 orifices are adapted to receive the telescopic sleeves 18 and 19 in the process of filling the pads. However, the dimensions of the said orifices and the telescopic sleeves are determined by the size of the sleeves in the pad to be filled, the 60 sleeves in the said pad being formed by sewing the said pad across its width as to form pockets for the stuffing to be blown into. It is also to be noted that the number of the orifices in the plate is determined by the number of sleeves 65 sewn in the pad to be filled. Also the size and number of the orifices in the plate is determined by the size and number of sleeves in the pads to be filled.

The same applies to the filling nozzles. However, as the stuffing mechanism is principally 70 designed for automobile pads where great quantities of similar size pads are to be stuffed, the sections in the pads are the same size and therefore only one set of plates is necessary. However 75 the mechanism is so designed as to permit

the majority of it to be used when another size pad having more or less stuffing and more or less sleeves formed in it is to be used, the amount of stuffing to be put in the pad being determined by the height of the mold, which 5 invention is described and claimed in my Patent Number 1,828,673 granted October 20, 1931, here- 10 fore mentioned.

The operation of my device is as follows:

Loading operators standing at adjacent ends 10 of the track load and unload molds, the operation of loading being, in the instance of this invention, different from that disclosed in my copending application, Serial Number 665,735 filed April 12, 1933. 15

In the present invention, the operator first slips the empty sections of a pad to be filled over the collars on the plate 37; the assembled collar and section is then positioned in the mold, the bottom of the collars resting on the friction 20 member 35 with the plate flush against the front edge of the bottom of the said mold. The hinged cover is then let down until the friction member 34 rests upon the upper edge of the collars. Slight pressure is placed on the 25 hinged top which causes the locking members 32 (which have been properly adjusted) to lock the mold in closed position, whereupon the sections are fixedly positioned on the various collars of the mold and the opening in the said 30 sections is distended as to permit entrance of the telescopic tube on the filling nozzle.

The filling process is similar to that employed in my co-pending applications, namely, the loaded mold is rolled to an operator who aligns 35 the telescopic tube with the number 1 orifice in the front plate. The said tube is pushed through the orifice to the rear end of the section and when the adjacent operator diverts the flow of stuffing material to the first-named operator, he slowly pulls the tube away from 40 the rear end of the sleeve and, as explained in my co-pending applications, the pad fills up ahead of the said nozzle.

When the end of the tube approaches the 45 front end of the mold, the operator diverts the flow to the adjacent operator who takes up the filling of another section of his pad, whereupon the first named operator pulls the tube clear of the plate 37 and moves the mold as to align orifice number 2. 50

By particular reference to Figures 7, 8 and 9, it will be seen that the form-giving collars 39 which surround the openings 38 and project into the mold serve not only as form-giving elements but as a means to align and guide the filling mediums or outlet elements 18 into position for filling the sections of the pad. Thus, the collars 39 serve the dual purpose of (1) aligning and guiding the filling mediums or 55 outlet elements 18 with the sections of the pad and (2) giving the sections of the pad the required form. 60

It is not thought necessary to go into detail respecting the process of loading the pads and the feeding of the pads to the operators as it is fully explained in the aforementioned co-pending applications, the difference in the construction of this invention being in the mold and nozzles, the difference in the mold being the mechanism for distending the pad as to permit the entrance and exit of the filling nozzle without the necessity of employing tubes or other mechanical means for distending the sleeves in the pad to be filled. Thus fixed nozzles may 70

be employed having telescopic tubes which remain on the nozzles at all times.

Having described my invention, what I claim and desire to secure by Letters Patent is:

- 5 1. In a mechanism for filling the sections of pads with a filling material from a column of such material in suspension, a combined guiding and supporting member having a plurality of openings and form giving collars extending from and registering with said openings for the selective, detachable and temporary reception of a medium for the supply of filling material and constituting guides for the filling medium, means to clamp portions of the sections to be filled about the said form giving collars preparatory to the detachable and temporary introduction and movement of said outlet element into and through said form giving collars and embodying yieldable pressure mediums engaging the sections of the pads, a pad mold having hingedly connected sections located at opposite sides of said pad, one of said sections of the mold being provided with a reticulated central portion for the passage of the suspension vehicle for the filling material, and a locking member holding the sections of the mold together and thus securing said yieldable pressure mediums in firm engagement with said sections of the pads.
- 10 2. In a mechanism for filling the sections of pads with a filling material from a column of such material in suspension, a combined guiding and supporting member having a plurality of openings and form giving collars extending from and registering with said openings for the selective, detachable and temporary reception of a filling medium and constituting guides for such filling medium, and means to secure portions of the sections to be filled about the said form giving collars preparatory to the detachable and temporary introduction of said filling medium into and through said form giving collars.
- 15 3. In a mechanism for filling the sections of pads with a filling material from a column of such material in suspension, a combined guiding and supporting member having a plurality of openings and form giving collars extending from and registering with said openings for the selective, detachable and temporary reception of a filling medium and constituting guides for such filling medium, and means to clamp portions of the sections to be filled about the said form giving collars preparatory to the detachable and temporary introduction and movement of said filling medium into and through said form giving collars.
- 20 4. In a structure for filling the sections of pads with a filling material suspended in a current of air, a mold for the reception of a pad, a combined guiding and supporting member associated with the mold and having a plurality of openings and form giving collars surrounding the openings and projecting into the mold for the detachable and temporary reception of a filling medium and constituting guides for such filling medium, and means to secure portions of the sections to be filled about the said form giving collars preparatory to the detachable and temporary introduction of said filling medium into and through said form giving collars.
- 25 5. In a mechanism for filling the sections of pads with a filling material from a column of such material in suspension, a combined guiding and supporting member having a plurality of openings and form giving collars extending from and registering with said openings for the selective, detachable and temporary reception of a filling medium and constituting guides for such filling medium, and means to clamp portions of the sections to be filled about the said form giving collars preparatory to the detachable and temporary introduction and movement of said filling medium into and through said form giving collars.
- 30 6. In a mechanism for filling the sections of pads with a filling material from a column of such material in suspension, a combined guiding and supporting member having a plurality of openings and form giving collars extending from and registering with said openings for the selective, detachable and temporary reception of a filling medium and constituting guides for such filling medium, and means to clamp portions of the sections to be filled about the said form giving collars preparatory to the detachable and temporary introduction and movement of said filling medium into and through said form giving collars.
- 35 7. In a mechanism for filling the sections of pads with a filling material from a column of such material in suspension, a combined guiding and supporting member having a plurality of openings and form giving collars extending from and registering with said openings for the selective, detachable and temporary reception of a filling medium and constituting guides for such filling medium, and means to clamp portions of the sections to be filled about the said form giving collars preparatory to the detachable and temporary introduction and movement of said filling medium into and through said form giving collars.
- 40 8. In a mechanism for filling the sections of pads with a filling material from a column of such material in suspension, a combined guiding and supporting member having a plurality of openings and form giving collars extending from and registering with said openings for the selective, detachable and temporary reception of a filling medium and constituting guides for such filling medium, and means to clamp portions of the sections to be filled about the said form giving collars preparatory to the detachable and temporary introduction and movement of said filling medium into and through said form giving collars.
- 45 9. In a mechanism for filling the sections of pads with a filling material from a column of such material in suspension, a combined guiding and supporting member having a plurality of openings and form giving collars extending from and registering with said openings for the selective, detachable and temporary reception of a filling medium and constituting guides for such filling medium, and means to clamp portions of the sections to be filled about the said form giving collars preparatory to the detachable and temporary introduction and movement of said filling medium into and through said form giving collars.

portion for the pasage of the suspension vehicle for the filling material.

3. In a mechanism for filling the sections of pads with a filling material from a flowing column of such material in suspension, a combined guiding and supporting member having a plurality of openings and form giving collars extending from and registering with said openings for the selective, detachable and temporary reception of a filling medium and constituting guides for such filling medium, and means to clamp portions of the sections to be filled about the said form giving collars preparatory to the detachable and temporary introduction and movement of said filling medium into and through said form giving collars, and a pad receiving mold carrying said clamping means.

4. In a structure for filling the sections of pads with a filling material suspended in a current of air, a mold for the reception of a pad, a combined guiding and supporting member associated with the mold and having a plurality of openings and form giving collars surrounding the openings and projecting into the mold for the detachable and temporary reception of a filling medium and constituting guides for such filling medium, and means to secure portions of the sections to be filled about the said form giving collars preparatory to the detachable and temporary introduction of said filling medium into and through said form giving collars.

5. In a mechanism for filling the sections of pads with a filling material from a column of such material in suspension, a combined guiding and supporting member having a plurality of openings and form giving collars extending from and registering with said openings for the selective, detachable and temporary reception of a filling medium and constituting guides for such filling medium, and means to clamp portions of the sections to be filled about the said form giving collars preparatory to the detachable and temporary introduction and movement of said filling medium into and through said form giving collars.

THOMAS L. McJOYNT.
